TELEPHONE UNIT

Edward Benisek, Geneva, and Hans Sengebusch,
 Villa Park, Ill., assignors to Associated Electric
 Laboratories, Inc., Chicago, Ill., a corporation of
 Delaware

Application February 26, 1940, Serial No. 320,790

13 Claims. (CL. 179—29)

The present invention relates to telephone units and more particularly to portable telephone units of the local battery type.

A conventional portable telephone unit of the local battery type utilized by linemen and others for test and general communication purposes is ordinarily relatively large and heavy, rendering transportation of the unit quite burdensome.

Accordingly, it is an object of the present invention to provide an improved portable telephone unit of the character noted which is of extremely simple and rugged construction and which is of light weight and relatively small size.

Another object of the invention is to provide a telephone unit comprising an improved supporting chassis for the station equipment of the unit, which chassis is constructed and arranged to provide a cradle adapted to receive and support the handle of a handset.

Another object of the invention is to provide in a telephone unit comprising a casing including a body and a removable cover for the body and a supporting chassis for the station equipment of the unit which is constructed and arranged to provide a cradle adapted to receive and support the handle of a handset, an improved arrangement including the cover for positively positioning the handle of a handset on the cradle when the cover occupies a closed position with respect to the body.

A further object of the invention is to provide a telephone unit comprising a supporting chassis for the station equipment of the unit, which chassis includes an improved rigid superstructure defining a battery compartment adapted to receive a battery forming a part of the station equipment of the unit.

In general, the objects as set forth above are attained in accordance with the present invention by providing, in a portable telephone unit of the character noted, a casing including a body provided with an open top and a removable cover for the open top of the body, a handset adapted to be housed in the casing when the cover occupies a closed position with respect to the body, a chassis disposed in the body and provided with a rigid superstructure including a base plate and a top plate, means for detachably securing the base plate to the body, station equipment supported by the superstructure of the chassis, the top plate being disposed adjacent the open top of the body and including spaced-apart and upwardly directed walls having aligned notches therein constituting cradle seats adapted to receive and support the handle of the handset,

and means carried by the cover and adapted to engage the handle of the handset when the cover occupies a closed position with respect to the body and the handle of the handset is supported on the cradle seats for positively positioning the handle of the handset on the cradle seats.

More particularly, the rigid superstructure of the chassis is formed by a number of structural members, including a base plate and a top plate arranged in spaced-apart relationship, and a pair of spaced-apart tubular supporting columns extending between the plates and secured in pairs of spaced-apart and aligned openings provided therein, the interiors of the tubular columns constituting battery compartments accessible through the aligned openings provided in the plates and adapted to receive batteries forming parts of the station equipment. Also the chassis carries a first common cover and battery terminal plate removably secured to the base plate over the pair of openings provided therein, and a second common cover and battery terminal plate removably secured to the top plate over the pair of openings provided therein. The station equipment comprises, in addition to the batteries mentioned, a hand generator provided with a rotatable operating shaft extending through an opening provided in one end wall of the body, the hand generator being supported upon the base plate, and a rotatable operating handle carried by the operating shaft. Also a first protective hood is carried by the one end of the body and surrounds the operating handle; and a protective generator shield is carried by the superstructure of the chassis and extends over the generator. Further a ringer is carried by the other end of the body; and a second protective hood is carried by the other end of the body and surrounds the ringer.

Further features of the invention pertain to the particular construction and arrangement of the telephone unit, whereby the above-outlined and additional operating features are attained.

The novel features believed to be characteristic of the invention are set forth with particularity in the appended claims. The invention, both as to its organization and method of operation, together with further objects and advantages thereof, will best be understood by reference to the following specification taken in connection with the accompanying drawings in which Figure 1 is a plan view of a portable telephone unit embodying the present invention; Fig. 2 is a longitudinal sectional view, partly broken away, of the telephone unit shown in

Fig. 1; Fig. 3 is an end elevational view, partly broken away, of the chassis of the telephone unit; and Fig. 4 is a side elevational view, partly broken away, of the chassis shown in Fig. 3.

Referring now more particularly to Figs. 1 and 2 of the drawings, there is illustrated a portable telephone unit embodying the features of the present invention and comprising a casing 10 including a body 11 and a cover 12, the cover 12 being pivotally mounted upon the upper rear wall of the body 11 by a longitudinally extending hinge 13. In order to facilitate movement of the casing 10 from place to place, a flexible carrying strap 14 formed of leather or the like is provided on the casing, the opposite ends of the carrying strap 14 being secured to the opposite end walls of the body 11 adjacent the upper edges thereof by rivets 15. Also the cover 12 carries a depending flange 16 which is adapted to overhang the upper wall of the body 11 when the cover 12 occupies its closed position with respect to the body 11, thereby to protect the apparatus housed in the casing 10 against inclement weather.

Preferably, both the cover 12 and the body 11 of the casing 10 are formed of a strong durable material such as metal reinforced plywood or a fibrous product. Also the corners of the body 11 and the cover 12 are specially reinforced by a number of metallic caps 17 secured thereto. Further the casing 10 is provided with a latching arrangement including two interengaging elements 18 and 19 respectively secured to the body 11 and the cover 12 and adapted to be latched together when the cover 12 occupies its closed position with respect to the body 11. Finally, the front wall of the cover 12 is provided with an opening therein and a cooperating fixture 20 which is constructed and arranged to permit an insulated cord to be extended from the exterior into the casing 10, while the cover 12 occupies its closed position with respect to the body 11.

The casing 10 houses a chassis 21, including a cradle 22, adapted to support a handset 23. The handset 23 comprises a handle 24, a receiver cup 25 carrying a receiver cell and an earpiece 26, and a transmitter cup 27 carrying a transmitter cell and mouthpiece 28. Also the handle 24 of the handset 23 houses a switch for controlling the encircling of the transmitter cell which is controlled by a rotatable operating button 29. The inner surface of the cover 12 has affixed thereto a block 30 which is adapted to engage the handle 24 of the handset 23 when the cover 12 occupies its closed position with respect to the body 11, thereby positively to clamp the handle 24 of the handset 23 in position with respect to the cradle 22 carried by the chassis 21. Preferably, the block 30 is formed of a compressible resilient material such as sponge rubber. Finally, the inner surface of the cover 12 carries a card 31 upon which a circuit diagram for the telephone unit and other instructions for the use of the telephone unit appear.

As best shown in Figs. 3 and 4 of the drawings, the chassis 21 comprises an open rigid superstructure formed by a substantially channel-shaped base plate 32, a substantially dish-shaped top plate 33 forming the cradle 22, two cylindrical tubular columns 34 and 35 and two posts 36 and 37, the tubular columns 34 and 35 being arranged in spaced-apart relationship adjacent one end of the chassis 21 and extending between the base plate 32 and the top plate 33; and the posts 36 and 37 being arranged in spaced-apart

relationship adjacent the other end of the chassis 21 and extending between the base plate 32 and the top plate 33. Preferably, the opposite ends of the posts 36 and 37 are secured to the base plate 32 and to the top plate 33 by a number of screws 38; while the opposite ends of the tubular columns 34 and 35 are secured to the base plate 32 and to the top plate 33 by a number of flanged connections 39. More particularly, the outer walls of the tubular columns 34 and 35, adjacent the opposite ends thereof, are turned down to provide tubular flanges on the opposite ends thereof, which tubular flanges project through cooperating pairs of spaced-apart openings respectively provided in the base plate 32 and in the top plate 33, the tubular flanges projecting through the cooperating pairs of openings provided in the base plate 32 and in the top plate 33 being peened or swaged over to provide the previously mentioned flanged connections 39. Two supporting rails 40 are provided in the channel-shaped base plate 32, adjacent the opposite ends thereof and secured in place by a number of screws 41, in order to facilitate positive placement of the chassis 21 within the body 11 of the casing 10. More particularly, the supporting rails 40 carried by the base plate 32 of the chassis 21 are directly secured to the bottom wall of the body 11 by a number of screws 42, thereby to provide for positive positioning of the chassis 21 within the body 11 and ready removal of the chassis 21 from the body 11 for purposes of inspection and repair.

Referring now more particularly to Figs. 2 and 4 of the drawings, each of the tubular columns 34 and 35 is adapted to receive and contain two batteries 43 of the dry cell type. In order to accommodate the batteries 43 and to prevent corrosion of the tubular columns 34 and 35, a cylindrical tubular insulating liner 44 formed of a fibrous material is arranged within each of the tubular columns 34 and 35, the insulating liner 44 being disposed between the inner wall of the tubular column and the batteries 43 disposed therein. The lower ends of the tubular columns 34 and 35 are at least partially closed by an insulated terminal plate 45 removably secured to the base plate 32 by a number of screws 46; while the upper ends of the tubular columns 34 and 35 are completely closed by a cover plate 47 removably secured to the top plate 33 by a thumb screw 48. Also it is noted that the cover plate 47 carries two helical coil springs 49 which are adapted to engage the end walls of the batteries 43 disposed in the associated tubular columns 34 and 35, thereby positively to make electrical connections with the batteries 43 and positively to hold the batteries in position. Further it is noted that the top plate 33 carries a terminal 50 which is electrically connected by the thumb screw 48 to the cover plate 47; while the terminal plate 45 carries two terminal screws 51 electrically connected to the batteries 43.

A substantially L-shaped generator shield 52 extends between the posts 36 and 37 and is secured thereto by a number of screws 53, the generator shield 52 being provided with an outwardly extending portion 54 overhanging one end of the base plate 32. Also an insulated main terminal block 55 is secured to the post 36 by a number of screws 56, the terminal block 55 being utilized to establish electrical connections between the various pieces of telephone apparatus housed in the casing 10, in a manner more fully explained hereinafter. In order to

provide the cradle 22, the top plate 33 is so formed that it includes a pair of spaced-apart cradle walls 57 having centrally disposed and aligned notches 58 formed therein, the notches 58 formed in the cradle walls 57 constituting 5 cradle seats adapted to receive the handle 24 of the handset 23.

In view of the above description of the construction and arrangement of the chassis 21, it will be understood that the tubular columns 34 and 35 not only serve to support the cradle 22 and to lend rigidity to the superstructure of the chassis 21 but they also serve as casings for the batteries 43; while the top plate 33 not only retains the tubular columns 34 and 35 in position 10 and lends rigidity to the superstructure of the chassis 21, but it is also formed to provide a unitary cradle 22 for supporting the handle 24 of the handset 23 within the casing 10.

The superstructure of the chassis 21 also supports an induction coil 59 and a condenser 60. More particularly, the induction coil 59 is secured to the top plate 33 by a number of screws 61 and is provided with a pair of terminals 62; while the condenser 60 is secured to the base 25 plate 32 in engagement with the tubular columns 34 and 35 by an arrangement comprising an angular bracket 63 and a number of screws 64 and is provided with a pair of terminals 65. Finally, the superstructure of the chassis 21 supports a hand generator 66 of the magneto type, the hand generator 66 being secured to the base plate 32 by a number of screws 67. More particularly, the hand generator 66 comprises a generator shaft 68, an operating shaft 69, a gear 35 train 70 disposed between the generator shaft 68 and the operating shaft 69 and a terminal plate 11. The operating shaft 69 is rotatable by an arrangement comprising a fixture 72 detachably secured thereto and a manually operable handle 73 carried by the fixture 72. The generator terminal plate 71 is formed of insulating material and carries a pair of cooperating contacts 74 which are actuated by the operating shaft 69; while the frame of the generator 66 is electrically insulated from the base plate 32 by a sheet of insulated material 75. It is noted that the operating shaft 69 extends through an opening 76 provided in one end of the body 11 of the casing 10, the fixture 72 being disposed partially within the opening 76. Preferably, the operating handle 73 is pivotally connected to the fixture 72 by a pivot pin 77 so that it may be pivoted into a non-operated and non-interfering position when the generator 66 is not in use. Finally the end wall of the body portion 11 of the casing 10 carries a cylindrical tubular generator hood 78 which projects outwardly in order to surround the fixture 72 and the operating handle 73 when the operating handle 73 occupies its non-operated position, thereby to protect the fixture 72 and the operating handle 73 against accidental injury. Further it is noted that the fixture 72 carried by the operating shaft 69 comprises a circular disk substantially overlapping the opening 76 provided in the end wall of the body 11 of the casing 10, thereby to prevent the entrance of moisture through the opening 76 in the end wall of the body 11 into the interior of the casing 10.

A ringer 79 of conventional construction and arrangement is removably secured to the opposite end wall of the body 11 exteriorly of the casing 10 by a screw 80 and is provided with insulated circuit leads 81 extending through an 75

opening 82 provided in the end wall of the body 11 into the interior of the casing 10, the circuit leads 81 being anchored in place by a clip 83 secured to the bottom wall of the body 11 of the casing 10. In order to protect the ringer 79 against accidental injury, a cylindrical tubular ringer hood 84 is carried by the end wall of the body 11 of the casing 10 which projects outwardly and surrounds the ringer 79. Finally, it is noted that the handset 23 is provided with an insulated cord 85; and two line terminal posts 86 and 87 are carried by the top plate 33. The line terminal posts 86 and 87 are insulated from the top plate 33 by two insulated sheets 88 positioned on the opposite sides thereof. Further it is noted that the line terminal posts 86 and 87 are disposed within the cavity provided in the dish-shaped top plate 33 and on opposite sides of the handle 24 of the handset 23 when the handset 23 is supported upon the cradle 22.

The circuit leads 81 extending to the ringer 79, the cord 85 extending to the handset 23, the terminals 82 of the induction coil 59, the terminals 65 of the condenser 60, the terminals 50 and 51 connected to the batteries 43, the generator terminal plate 71 and the two line terminal posts 86 and 87 are connected to the main terminal block 55 and then interconnected to provide an operating circuit network for the various pieces of telephone equipment housed in the casing 10. The operating circuit network for the various pieces of telephone equipment may be connected and arranged in any suitable manner. However, it is preferable that this circuit network be connected and arranged in the manner disclosed in the copending application of Harold C. Pye, Serial No. 320,743, filed Feb. 26, 1940.

It will be understood that, during the operation of the telephone unit, a person thereat may be signaled over an associated telephone line from a distant station by the operation of the ringer 79 and may signal a distant station over the associated telephone line by operating the hand generator 66. Also it will be understood that the person at the telephone unit may receive a message over the associated telephone line by way of the receiver of the handset 23 and may transmit a message over the associated telephone line by way of the transmitter of the handset 23. At this point it is noted that the transmitter of the handset 23 may be encircuited with respect to the batteries 43 and the associated telephone line by operating the switch housed in the handle 24 of the handset 23 by means of the rotatable operating button 29, the telephone unit being of the local battery type.

In view of the foregoing description of the construction and arrangement of the telephone unit, it will be understood that only the ringer 79 is directly carried by the body 11 of the casing 10, the remainder of the telephone equipment including the handset 23, the batteries 43, the induction coil 59, the condenser 60 and the hand generator 66 being directly carried by the chassis 21. Further it is noted that, when the handle 24 of the handset 23 occupies its normal position with respect to the supporting cradle 22, the receiver and earpiece 26 thereof overhangs the hand generator 66, the outwardly extending portion 54 of the generator shield 52 serving to define within the casing 10 a hand generator compartment and an adjacent receiver compartment. Further, when the handle 24 of the handset 23 occupies its normal position with respect to the supporting cradle 22, the transmitter and mouthpiece 28

thereof are disposed in a transmitter compartment defined between the tubular columns 34 and 35 and the adjacent end wall of the body 11 of the casing 10. Also the chassis 21 and the telephone equipment carried thereby may be readily removed from the body 11 of the casing 10 for purposes of inspection and repair by detaching the fixture 12 from the operating shaft 69 and by removing the screws 42. Further it is noted that, when the cover 12 occupies its open position with respect to the body 11, the handle 24 of the handset 23 may be readily removed and replaced with respect to the cradle 22 carried by the chassis 21; and that, when the cover 12 occupies its closed position with respect to the body 11, the handle 24 of the handset 23 is positively retained in place with respect to the cradle 22 carried by the chassis 21 by the block 30. Finally, it is noted that the casing 10 may be conveniently moved from place to place by the carrying strap 14; while the handle 73 of the hand generator 66 and the ringer 79 are positively protected against accidental injury due to the provision of the respective hoods 78 and 84 carried by the opposite end walls of the body 11 of the casing 10.

While there has been described what is at present considered to be the preferred embodiment of the invention, it will be understood that various modifications may be made therein and it is intended to cover in the appended claims all such modifications as fall within the true spirit and scope of the invention.

What is claimed is:

1. A portable telephone unit comprising a casing including a body provided with an open top and a removable cover for the open top of said body, a chassis disposed in said body and provided with a rigid superstructure including a base plate and a top plate, means for detachably securing said base plate to said body, and station equipment supported by the superstructure of said chassis, said top plate being disposed adjacent the open top of said body and including spaced-apart and upwardly directed walls having aligned notches therein constituting cradle seats adapted to receive and support the handle of a handset housed in said casing when said cover occupies a closed position with respect to said body.

2. A portable telephone unit comprising a casing including a body provided with an open top and a removable cover for the open top of said body, a chassis disposed in said body and provided with a rigid superstructure including a base plate and a top plate, station equipment supported by the superstructure of said chassis, said station equipment including a hand generator provided with a rotatable operating shaft extending through an opening provided in one end of said body, a rotatable operating handle carried by said operating shaft, a first protective hood carried by the one end of said body and surrounding said operating handle, a protective generator shield carried by the superstructure of said chassis and extending over said generator, a ringer carried by the other end of said body, and a second protective hood carried by the other end of said body and surrounding said ringer, said top plate being disposed adjacent the open top of said body and including spaced-apart and upwardly directed walls having aligned notches therein constituting cradle seats adapted to receive and support the handle of a handset housed in said casing when said cover occupies a closed position with respect to said body.

3. A portable telephone unit comprising a cas-

ing including a body provided with an open top and a removable cover for the open top of said body, a handset adapted to be housed in said casing when said cover occupies a closed position with respect to said body, a chassis disposed in said body, station equipment supported by said chassis, a cradle carried by said chassis, said cradle being disposed adjacent the open top of said body and adapted to receive and support the handle of said handset, and means carried by said cover and adapted to engage the handle of said handset when said cover occupies a closed position with respect to said body and the handle of said handset is supported on said cradle for positively positioning the handle of said handset on said cradle.

4. A telephone unit comprising a chassis provided with a rigid superstructure formed by a number of structural members including a tubular member, and station equipment including a battery supported by the superstructure of said chassis, said battery being supported within said tubular member.

5. A telephone unit comprising a chassis provided with a rigid superstructure formed by a number of structural members including a tubular member, and station equipment supported by the superstructure of said chassis, the interior of said tubular member constituting a battery compartment adapted to receive a battery forming a part of said station equipment.

6. A telephone unit comprising a chassis provided with a rigid superstructure formed by a number of structural members including a tubular supporting column, and station equipment supported by the superstructure of said chassis, the interior of said tubular column constituting a battery compartment adapted to receive a battery forming a part of said station equipment.

7. A telephone unit comprising a chassis provided with a rigid superstructure formed by a number of structural members including a pair of spaced-apart plates and a pair of spaced-apart tubular members extending between and secured to said plates, and station equipment supported by the superstructure of said chassis, the interiors of said tubular members constituting battery compartments adapted to receive batteries forming parts of said station equipment.

8. A telephone unit comprising a chassis provided with a rigid superstructure formed by a number of structural members including a base plate and a top plate arranged in spaced-apart relationship and a pair of spaced-apart tubular supporting columns extending between and secured to said plates, and station equipment supported by the superstructure of said chassis, the interiors of said tubular columns constituting battery compartments adapted to receive batteries forming parts of said station equipment.

9. A telephone unit comprising a chassis provided with a rigid superstructure formed by a number of structural members including a tubular member, station equipment supported by the superstructure of said chassis, the interior of said tubular member constituting a battery compartment adapted to receive a battery forming a part of said station equipment, and a cradle carried by said chassis and adapted to receive and support the handle of a handset.

10. A telephone unit comprising a chassis provided with a rigid superstructure formed by a number of structural members including a top plate and a tubular supporting column secured to said top plate, and station equipment supported

by the superstructure of said chassis, the interior of said tubular column constituting a battery compartment adapted to receive a battery forming a part of said station equipment, said top plate constituting a cradle adapted to receive and support the handle of a handset.

11. A portable telephone unit comprising a casing, a chassis housed in said casing and provided with a rigid superstructure formed by a number of structural members including a base plate and a top plate arranged in spaced-apart relationship and a tubular supporting column extending between and secured to said plates, and station equipment supported by the superstructure of said chassis, the interior of said tubular column constituting a battery compartment adapted to receive a battery forming a part of said station equipment, said top plate including spaced-apart and upwardly directed walls having aligned notches therein constituting cradle seats adapted to receive and support the handle of a handset housed in said casing.

12. A portable telephone unit comprising a casing, a chassis housed in said casing and provided with a rigid superstructure formed by a number of structural members including a base plate and a top plate arranged in spaced-apart relationship and a tubular supporting column extending between said plates and secured in aligned openings provided therein, station equipment supported by the superstructure of said chassis, the interior of said tubular column constituting a battery compartment accessible through the aligned opening provided in said top plate and adapted to receive a battery form-

10

ing a part of said station equipment, and a cover and battery terminal plate removably secured to said top plate over the opening provided therein, said top plate including spaced-apart and upwardly directed walls having aligned notches therein constituting cradle seats adapted to receive and support the handle of a handset housed in said casing.

13. A portable telephone unit comprising a casing, a chassis housed in said casing and provided with a rigid superstructure formed by a number of structural members including a base plate and a top plate arranged in spaced-apart relationship and a pair of spaced-apart tubular supporting columns extending between said plates and secured in pairs of spaced-apart and aligned openings provided therein, station equipment supported by the superstructure of said chassis, the interiors of said tubular columns constituting battery compartments accessible through the aligned openings provided in said plates and adapted to receive batteries forming parts of said station equipment, a first common cover and battery terminal plate removably secured to said base plate over the pair of openings provided therein, and a second common cover and battery terminal plate removably secured to said top plate over the pair of openings provided therein, said top plate including spaced-apart and upwardly directed walls having aligned notches therein constituting cradle seats adapted to receive and support the handle of a handset housed in said casing.

EDWARD BENISEK.
HANS SENGBUSCH.
